(57) **CLAIM**

(21) Appl. No.: **29/193,382**

The ornamental design for a walk behind rotary trowel guide handle, as shown and described.

(22) Filed: **Nov. 7, 2003**

DESCRIPTION

(51) LOC (7) Cl. **08-05**

FIG. 1 is a perspective view of a walk behind rotary trowel guide handle, wherein the dashed lines illustrate the environment and form no part of the claimed design; FIG. 2 is a top plan view of the guide handle of FIG. 1; FIG. 3 is a front elevation view of the guide handle of FIG. 1;

(52) U.S. Cl. **D8/107**

FIG. 4 is bottom plan view of the guide handle of FIG. 1; FIG. 5 is a left side elevation view of the guide handle of FIG. 1, the right side elevation view being a mirror image thereof; and, FIG. 6 is a rear elevation view of the guide handle of FIG. 1.
